WEIGHT INDICATING AND PRINTING
MECHANISM

Alan J. Jerome, Toledo, Ohio, assignor to Toledo
Scale Manufacturing Company, Toledo, Ohio,
a corporation of New Jersey

Application September 23, 1935, Serial No. 41,739

7 Claims. (Cl. 265—5)

This invention relates to weight indicating and printing mechanisms, and one of its objects is to provide weight indicating and printing mechanism having a large number of indicating and printing indicia on a comparatively small printing disk.

Another object of the invention is to provide load-counterbalancing mechanism with a printing disk so connected thereto, by means of a single rack and comparatively large pinion, as to turn through a plurality of revolutions.

Another object of the invention is to provide weighing mechanism having a printing disk so connected thereto as to be given a combined translative and rotative movement.

Another object is to provide a disk bearing a spiral series of indicia, with a combination of means for so moving the disk that such indicia are selectively brought into required position.

Another object is to provide weighing mechanism with a disk having a spiral series of indicia and so connected to the weighing mechanism as to have combined translative and rotative movement, and auxiliary means for selectively moving said indicia exactly into required position.

Other objects and advantages will be apparent from the following description, in which reference is had to the accompanying drawings illustrating a preferred embodiment of my invention and wherein similar reference numerals designate similar parts throughout the several views.

In the drawings:—

Figure I is a rear elevational view of the upper part of an automatic weighing scale frame showing automatic load-counterbalancing mechanism having a printing disk connected thereto for combined translative and rotative movement;

Figure II is an enlarged elevational view, with parts broken away and parts in section substantially on the line II—II of Figure I, showing printing mechanism and auxiliary exact-positioning means in co-operative relation to the printing disk;

Figure III is a further enlarged front elevational view taken on the line III—III of Figure II;

Figure IV is a fragmentary front elevational view of the disk which forms an element of my invention;

Figure V is an enlarged fragmentary elevational view taken from the position indicated by the line V—V of Figure I; and

Figure VI is a wiring diagram showing electrical circuits and electrical apparatus incorporated in the printing mechanism employed in the device of my invention.

Referring to the drawings in detail, the weighing scale frame includes an upright column or standard, a fragment 1 of which is shown in Figure I. Supported thereon is a circular housing 2, within which is fixed a sector guide 3 having flexible metallic ribbons 4 depending from fastenings 5 by means of which the ribbons are secured at their upper ends to the sector guide. Secured to the lower ends of the ribbons 4, by means of fastenings 6, are fulcrum sectors 7 which are parts of rigid pendulum assemblies that also include power sectors 8 and pendulum weights 9. A pair of flexible metallic power ribbons 10 overlie the curved faces of the power sectors 8 and are secured thereto, at 15 their upper ends, by means of fastenings 11. The lower ends of the power ribbons 10 are secured to a yoke 12 which is connected by means of a hook 13 to a lever 14, the lever 14 in turn being connected by means of a rod 15 to the load-supporting lever mechanism (not shown) of the scale. Pivotaly supported by means of ball bearings 16 on axes lying at the centers of curvature of the fulcrum sectors 7 is a floating frame 17 and journaled in the frame 17 by means of ball 20 bearings 18 is a rotatable shaft 19 upon which is fixed a pinion 20. Fixed upon the forward end of the shaft 19 is a thin, light disk 21 which has a spiral series of raised printing indicia 22 etched or otherwise formed upon its face and 25 which is provided also with a parallel series of indicating indicia 23. A rack 24 is pivotally connected at its lower end to the yoke 12 and meshes with the pinion 20, being gently held in engagement therewith by the effect of gravity on a 30 small weight 25 and prevented from jumping out of engagement by roller 26 which is carried by the floating frame 17 in juxtaposition of the back of the rack 24 but normally out of engagement 35 with the rack.

When a load is placed on the commodity-receiver of the weighing scale a downward pull is exerted on the rod 15 and the force of the pull is transmitted through the lever 14, the hook 13 and the yoke 12 to the power ribbons 10, which 40 act upon the power sectors 8 to swing the pendulum weights 9 outwardly and upwardly until the load on the commodity-receiver is counterbalanced. As the pendulum weights 9 swing outwardly and upwardly the fulcrum sectors 7 roll 45 upwardly on their supporting ribbons 4 and the ball bearings 16 at the centers of curvature of the fulcrum sectors move vertically upwardly, thus carrying vertically upwardly the floating frame 17, the shaft 19, as well as the pinion 20 50

55

and disk 21 which are fixed upon the shaft 19. Meanwhile the yoke 12 and the rack 24 are pulled downwardly, and, since the rack 24 is moving in a downward direction, while the shaft 19 moves 5 in an upward direction, the pinion 20, the shaft 19 and the disk 21 are rotated through more degrees of revolution than would be the case if the rotation were due to the downward movement of the rack alone or to the upward movement of 10 the shaft 19 alone. The parts are so proportioned that when the pendulum weights 9 swing from zero position to full capacity position, the pinion 20, shaft 19 and disk 21 are rotated through two full revolutions, and because of the 15 large relative movement of the rack and pinion, such double rotation is effected with the use of a comparatively large pinion, thus minimizing wear on the rack and pinion and rendering inappreciable the effects of slight variations in the form 20 of the rack and pinion teeth.

Mounted upon the scale frame, as best shown in Figure II, in position to print records from the raised indicia 22 of the disk 21, is a printing device of the type illustrated and described in 25 United States patent to Williams No. 1,864,570. The printing device consists principally of a solenoid 27 which acts through toggle links 28 to press a platen 29 and an abutment 30 toward 30 each other on opposite sides of the printing disk 21. Between the platen 29 and the printing disk are an inking ribbon 31 and a strip of paper 32. As the platen and abutment frame move toward 35 each other on opposite sides of the disk the inking ribbon 31 is pressed against the paper strip and the paper strip is pressed against the raised indicia 22, while pressure from the opposite direction is exerted upon the disk by the abutment 30. The effect of thus squeezing the inked ribbon and paper and the disk together is to cause 40 to be imprinted upon the paper an inked impression of whatever raised indicia are between the platen and abutment. The spiral series of indicia 22 is so located on the disk 21 that as the disk rotates and moves upwardly, the indicia, beginning with the zero indicium, are successively 45 carried between the platen and the abutment.

In order that the printing operation may not take place while a portion of the disk intermediate between two adjacent indicia is in printing 50 position, I have provided auxiliary final indicium positioning means which is carried by the floating frame 17. The positioning means includes a bracket 33 to which is fixed a horizontal guide 34. Carried by the bracket 33 is a magnet 35 having a pivoted armature 36 to which is fixed a depending arm 37 connected at its lower end, by 55 means of a link 38, to a channel member 39 which is supported upon and is movable longitudinally of the guide 34. In order to minimize 60 friction between the guide 34 and channel member 39, bearing balls are interposed between them. Fixed to the channel member 39 is a flanged plate 40 and mounted in openings in the flanges of the flanged plate 40 are plungers 41 having cone-shaped ends which, when the magnet 35 is actuated, are pushed against the disk 21. The disk 21 is provided with a circular series of openings 42 which are so spaced and located relatively to the location of the plungers 41 that the cone-shaped end of at least one of the plungers will 70 always engage in one of the openings 42. The plungers are slidably mounted in the flanges of the flanged plate 40 and are yieldably held in extended position by means of springs 43. The 75 ends of two of the plungers are rounded, as in-

dicated at 44 and 45 of Figure III, so that if one of the rounded ends should enter one of the openings 42 at the same time that one of the unrounded ends enters another opening, the rounded end will be cammed out of its opening and the unrounded end will act to exactly position the disk. The positioning device is not, per se, of my invention and I have described it, therefore, only in such detail as will serve to show its function in the operation of my device. 10

In order to provide a visible indication of the weight on the scale, a window provided with a magnifying lens 46 is located in front of the series of indicia 23. When one of the series of indicia 22 is in position for printing, an indicium of the 15 same value in the series 23 is visible through the lens 46. An index 47 is provided to show which of the indicia 23 is to be read, and the indicia are illuminated by means of a lamp 48. 20

Alternating current from a source of power G (see Figure VI) energizes the lamp 48 and is supplied also, by means of a wire 49, to a rectifier 50. The return circuit from the rectifier 50 includes the wire 51 leading from the rectifier to the transitory switch 52 which is connected 25 to the other side of the generator by the wire 53. Hence, when the transitory switch 52 is closed, the rectifier 50 is energized and direct current from the output side of the rectifier 50 passes through the wire 54 to the primary relay 30 55 and thence, through the wire 56, the connection 57, the wire 58, the magnet 35, the switch 63, the connection 61 and the wire 62, back to the rectifier 50. Passage of the direct current through the primary relay 55 closes the switch 63, thus maintaining the alternating current supply to the rectifier after the opening of the transitory switch 52 which takes place automatically shortly after it is closed, and passage of direct current through the magnet 35 moves 35 the plungers 41 forward to accurately position the disk and closes the switch 64, thus energizing the solenoid 27 which actuates the toggles 28 to force the platen 29 and abutment 30 toward each other and thus cause a printed record to be made 40 on the paper strip 32. One side of the switch 60 is connected to the solenoid core, so that as the core approaches the end of its stroke, the switch 60 is opened, thus de-energizing the primary relay 55 and the magnet 35. De-energization 45 of the primary relay 55 opens the alternating current circuit to the rectifier 50 and de-energization of the magnet 35 opens the circuit through the coil of the solenoid 27, permitting the solenoid core to descend and re-close the switch 60. The 50 electrical circuits and electrical apparatus thus 55 returned to the condition in which they are shown in Figure VI.

The embodiment of my invention herein shown and described is to be regarded as illustrative 60 only, and it is to be understood that the invention is susceptible to variation, modification and change within the spirit and scope of the subjoined claims.

Having described my invention, I claim: 65

1. In a device of the class described, in combination, automatic load-counterbalancing mechanism, said automatic load-counterbalancing mechanism having a point movable in a straight line under the influence of loads counterbalanced thereby, a disk having its axis connected to said automatic load-counterbalancing mechanism at the point which is movable in a straight line, whereby said disk is given translative and rotative movement by movement of 70 75

said automatic load-counterbalancing mechanism, a spirally arranged series of readable indicia on said disk, and means for rendering visible certain of said readable indicia indicative of 5 weights of loads counterbalanced by said load-counterbalancing mechanism.

2. In a device of the class described, in combination, load-counterbalancing pendulum mechanism, said pendulum mechanism having a point 10 movable in a straight line under the influence of loads counterbalanced by said pendulum mechanism, a disk, means connecting the axis of said disk to said pendulum mechanism at the point which is movable in a straight line where- 15 by the axis of said disk is moved with said point, and means for causing said disk to rotate during such movement, said disk being provided with a spirally arranged series of indicia which are successively moved through a given position during movement of said disk. 20

3. In a device of the class described, in combination, load-counterbalancing pendulum means, a disk bearing a spirally arranged series of indicia, means for connecting said disk to 25 said pendulum load-counterbalancing means to move the axis of said disk in a straight path upon movement of said pendulum load-counterbalancing means, and means for causing said disk to rotate during such straight path movement of 30 its axis whereby the indicia of said spirally arranged series are successively moved through a given position.

4. In a device of the class described, in combination, load-counterbalancing pendulum 35 means, a disk bearing a spirally arranged series of indicia, means for connecting said disk to said pendulum load-counterbalancing means to move the axis of said disk in a straight path upon movement of said pendulum load-counter- 40 balancing means, means for causing said disk to rotate during such straight path movement

of its axis whereby the indicia of said spirally arranged series are successively moved through a given position, and auxiliary means for exactly positioning said indicia.

5. In a device of the class described, in 5 combination, automatic load-counterbalancing mechanism, a rotatable shaft, means connecting said rotatable shaft to said load-counterbalancing mechanism to move said shaft transversely, a disk fixed to said shaft, and means operable 10 upon such transverse movement of said shaft to rotate said disk, said disk bearing indicia arranged thereon to be successively moved through a given position by such transverse and rotative movement. 15

6. In a device of the class described, in combination, automatic load-counterbalancing mechanism, a rotatable shaft, means connecting said rotatable shaft to said load-counterbalancing mechanism to move said shaft transversely, 20 a disk fixed to said shaft, means operable upon such transverse movement of said shaft to rotate said disk, said disk bearing indicia arranged thereon to be successively moved through a given position by such transverse and rotative movement, 25 and means for printing records from such indicia.

7. In a device of the class described, in combination, automatic load-counterbalancing mechanism, a rotatable shaft, means connecting 30 said rotatable shaft to said load-counterbalancing mechanism to move said shaft transversely, a disk fixed to said shaft, means operable upon such transverse movement of said shaft to rotate said disk, said disk bearing indicia arranged 35 thereon to be successively moved through a given position by such transverse and rotative movement, means for printing records from such indicia, and auxiliary means for exactly positioning said indicia for printing. 40

ALAN J. JEROME.
